DESIGN FOR A COMBINED ELASTIC SHOELACE AND FASTENER

Benjamin S. Richmond, Brighton, Mass.

Application November 30, 1945, Serial No. 124,242

Term of patent 7 years

(Cl. D7—6)

To all whom it may concern:

Be it known that I, Benjamin S. Richmond, a citizen of the United States residing at Brighton, in the county of Suffolk and State of Massachusetts, have invented a new, original, and ornamental Design for a Combined Elastic Shoe Lace and Fastener of which the following is a specification; reference being had to the accompanying drawing, forming part thereof.

Fig. 1 is a side elevational view of a combined elastic shoe lace and fastener showing my new design; and

Fig. 2 is a plan view of the same.

I claim:

The ornamental design for a combined elastic shoe lace and fastener, substantially as shown.

BENJAMIN S. RICHMOND.
